UNITED STATES PATENT OFFICE.

LOUIS DELLETT, OF BROOKLYN, NEW YORK.

CHAIR.

Application filed December 3, 1925. Serial No. 73,087.

An object of the present invention is to provide a chair so constructed that a number of the chairs may be conveniently nested for the purpose of storage.

5 A more specific object of the invention is to provide a non-folding sheet metal chair formed with inclined tapering legs adapted for nesting one within the other, so that a number of the chairs may be piled or nested 10 in direct vertical juxtaposition.

Further objects are to provide a chair of simple, practical construction which will be rugged and durable in use, and which will be well suited to the requirements of economical manufacture.

With the above noted and other objects in view, the invention consists in certain novel features of construction and combinations and arrangements of parts, as will be 20 more fully hereinafter set forth and pointed out in the claims. The invention may be more fully understood from the following description in connection with the accompanying drawings, wherein

25 Fig. 1 is a top plan view of a chair embodying the invention, the chair seat being omitted.

Fig. 2 is a view in side elevation thereof.

Fig. 3 is a view in rear elevation thereof.

30 Fig. 4 is a side elevational view showing a number of chairs in superimposed nested relationship.

Fig. 5 is an enlarged sectional detail on the line 5—5 of Fig. 4.

35 Fig. 6 is a sectional detail on the line 6—6 of Fig. 2.

It is to be understood that while the drawings are illustrative of a preferred embodiment of the invention, the particular shape 40 of the chair seat, shape of the back, and the details of construction are subject to a wide variety of variations.

The chair which is preferably formed of sheet metal, includes a seat frame 10 which 45 may be of octagonal shape, including relatively long side portions, and relatively short corner portions. The legs 11 of the chair are preferably approximately semi-circular in cross section with the concave portions 50 turned inwardly. At their upper ends, the legs are flanged as indicated at 12 and secured to the corners of the seat frame 10 by welding, riveting or in any other appropriate or convenient manner. The seat frame may 55 be reinforced by suitable means such as the V-shaped braces 13, and the connection of

the legs with the seat frame is strengthened by the use of diagonal bracing members 14 connecting the sides of the legs with the exterior of the seat frame. 60

It is to be noted that the legs incline outwardly from their upper ends to the feet 15, so that a number of chairs may be conveniently nested in the manner shown in Figs. 4 and 5. When the chairs are superimposed 65 one upon the other, the concave inner faces of the tapering legs of one chair, nest with the convex outer face of the tapering legs of a subjacent chair, and the seat frames of the various chairs directly engage to limit 70 the relative telescoping movement of the legs.

It is of course essential to provide a chair back which will not interfere with the proper nesting of the chairs. The shape or design of the back is subject to a wide 75 variety of variations. I have shown a back which includes a series of uprights 16 secured at their lower ends to the exterior of the rear face of the seat 10, said uprights supporting and preferably being integral 80 with a back rest portion 17. It will be noted that the uprights at their lower ends are bevelled as indicated at 18, this bevel being at an angle similar to the angle at which the uprights slant rearwardly. When the chairs 85 are nested, the bevelled rear lower ends of the uprights of one chair will lie flatly against the front face of the inclined uprights of a subjacent chair, and the backs will in no way interfere with the proper 90 nesting of the chairs.

Obviously numerous changes and alterations might be made in the general form and arrangement of parts described, without departing from the invention. Hence 95 I do not wish to limit myself to the details set forth, but shall consider myself at liberty to make such changes and alterations as fairly fall within the spirit and scope of the appended claims. 10

I claim:

1. As a new article of manufacture, a chair including a seat frame, sheet metal legs connected at their upper ends to the seat frame, said legs being of arcuate cross section with 10 the channelled portions turned inwardly whereby the legs of a number of chairs may be nested, a chair back secured to the rear of the seat frame and inclined away from the frame, said back at its lower end including a rear face bevelled on the same angle at which the chair back is inclined, whereby 11

the backs will not interfere with nesting of the chairs.

2. As a new article of manufacture, a chair including a metal seat frame formed of a strip of metal bent into the desired shape, sheet metal legs connected at their upper ends to the outer face of the seat frame, said legs being of arcuate cross section with chan-

nelled portions turned inwardly, whereby the legs of a number of chairs may be nested, a 10 chair back secured to the rear of the outer face of the rear of the seat frame, and being sufficiently narrow at its lower end so that it may be straddled by the legs of superimposed nested chairs.

LOUIS DELBERT.
